UNITED STATES PATENT OFFICE.

NED WINKLER, OF ST. ALBANS, WEST VIRGINIA.

ADVERTISING DEVICE.

Application filed January 10, 1922. Serial No. 523,308.

To all whom it may concern:

Be it known that I, NED WINKLER, a citizen of the United States, and a resident of St. Albans, in the county of Kanawha, 5 in the State of West Virginia, have invented certain new and useful Improvements in Advertising Devices, of which the following is a specification.

This invention relates to advertising devices especially adapted for use in store fronts and the like.

An important object of this invention is to provide an advertising device having oppositely movable belts upon which figures 15 are mounted to represent an endless line of purchasers entering a store and a similar line leaving the store laden with bundles.

A further object is to provide an advertising device having novel means whereby a 20 plurality of display cards are separably exposed to view.

Further the invention forming the subject matter of this application aims to provide a display device of the character specified which is of highly simplified construction, attractive in appearance and cheap to manufacture.

In the accompanying drawing forming a part of this application and in which like 30 numerals are employed to designate like parts throughout the same,

Figure 1 is a perspective of the improved display device.

Figure 2 is a fragmentary perspective illustrating the endless belts for supporting the movable figures.

Figure 3 is a horizontal sectional view through the operating pulleys for supporting the endless belts, the endless belts also 40 being shown in section.

Figure 4 is a vertical sectional view through the improved display device.

Figure 5 is a vertical transverse sectional view through the device, the view being 45 taken at right angles to Figure 4.

In the drawing wherein for the purpose of illustration is shown a preferred embodiment of the invention the numeral 5 generally designates a casing which may be arranged in the show case at the front of the store or in any other convenient or desirable place. As illustrated in Figure 1 the casing 5 consists of upstanding side walls 6, a bottom 7, a top 8 and a front wall 9, 55 the wall 9 being provided with a door 10

which affords access to several of the movable parts of the device.

As illustrated in Figures 4 and 5 a main drive shaft 12 is arranged in the lower portion of the casing and is supported by the 60 bearing 13 secured to the back of the casing and is rotatably extended through the front wall 9. A drive pulley 14 is keyed or otherwise secured to the main drive shaft 12 and has connection with an electric motor 65 15 by means of an endless belt or drive pulley 16. If desired a clock mechanism may be employed in lieu of the electric motor 15, for driving the shaft.

The drive shaft 12 is extended out 70 through the front of the casing and supports a disk 18 from which a plurality of pins 19 or the like extend. Suitable display cards 20 are suspended from the pins 19 by means of attaching wires 21, the said 75 attaching wires 21 being loosely connected to the pins 19 so that the display cards 20 which may bear advertising matter are always located beneath the pins 19. Display devices of any desired type may be employed 80 in lieu of the display cards 20 and as the display cards move continuously, they will attract the attention of those passing the display device. The display disk 18 may be secured on the shaft 12 by any suitable 85 means and is arranged exteriorly of the casing to be within the view at all times.

With reference to Figures 4 and 5 it will be observed that a plurality of vertically movable display cards 22 are arranged with 90 in the casing and when elevated appear directly behind the glass 23 in the front door 10 of the casing so that the cards are individually viewed through the glass. Each card 22 is mounted on the upper end 95 of a vertically movable rod 24 slidable through upper and lower guides 25 of any suitable type. The upper end of each rod or card supporting member is provided with a transverse slot to detachably receive the 100 card whereby the card may be readily changed when desired.

The several vertically movable card supporting members 24 are actuated by means of cams 28 having hubs 29 keyed or otherwise secured to the shaft 12 so that the several cams 28 will be caused to rotate with the shaft. The cams 28 correspond in number to the card operating members 24 and engage the lower ends of the same so that 110

when the shaft is rotated in a clockwise direction the rounded outer edges 30 of the cams will be presented to the rods 24 for elevating the same. As each cam reaches the limit of its upward movement, the flat end 33 of the same is in engagement with the lower end of the adjacent rod 24 so that the exposed cards 22 remain in its elevated position for approximately 10 or 15 seconds and when the flattened outer end 33 of the cam moves beyond the lower end of the rod 24, the lower end of the rod will move downwardly into engagement with the straight edge 34 of the cam. As the cam continues to rotate the lower end of the rod engages the hub 29 and the rounded outer edge 30 of the cam again comes into contact with the rod as the rounded outer edge of the cam is in the arc of the same circle as the hub. It is thus seen that the several cams 28 which are arranged in spaced relation on the shaft serve as an efficient and reliable means for separately exposing the display cards 22. The cams 28 are maintained in spaced relation by hubs 29 or by means of other spacing devices, such as washers.

The improved display device is also provided with means whereby a stream of people are seen to be entering the store and a second stream of people who are seen to be leaving the store laden with bundles. This feature of the invention consists of an endless belt 40 having a plurality of figures 41 secured thereto in any suitable manner and representing people entering the store with a view of making purchases. Therefore the figures are not provided with parcels or bundles but are preferably empty handed. As illustrated clearly in Figures 1 and 2 a second endless belt 43 is arranged at one side of the endless belt 40 and is provided with a plurality of spaced figures 44 representing people leaving the store laden with purses made in the store, all of which is intended to advertise the popularity of a particular store and to attract the attention of passers-by. The two endless streams of people or figures representing the people pass by a sight opening 48 in the door 10 and may be readily seen by the passers-by.

Each endless belt is supported by a pulley 49 and by a second pulley 50. It is important to note that each pulley 49 is keyed or otherwise secured to a shaft 52 while each pulley 50 is loosely mounted or rotatably mounted on the other shaft 52. It is thus seen that each shaft has rigid connection with one pulley 49 and loosely supports one pulley 50.

The drive shaft 52 for each endless belt rotates in opposite directions so that the endless belts are caused to be moved in opposite directions.

One of the streams of people is therefore

seen to go in one direction and the other stream of people is seen to go in the other direction.

With reference to Figure 2 it will be observed that pulleys 54 are rigidly secured to the several shafts 52 and have connection with drive belts 55 trained about larger pulleys 56 on a pair of shafts 57. The shafts 57 of which there are two are preferably mounted beneath the shaft 52 and are provided with sprocket wheels 58 having connection with a sprocket chain 59. The sprocket chain 59 is trained about a sprocket wheel 60 secured in any suitable manner on the shaft 12.

Referring again to the drive belt 55 it will be seen that one of the belts is twisted so that the two pulley supporting shafts 52 rotate in opposite directions.

At one end of the sight opening 48 a miniature store is provided and the figures 41 are seen to enter the store while the figures 44 are seen to leave the store. A suitable glass is provided in the sight opening 48 and any desired number of figures may be made to appear in the sight opening at a given time.

In operation, the motor 15 is started so that the shaft 12 is operated. This causes the several streams of people to enter and leave the store and also causes the cards 22 to be separately exposed. This movement of the people across the sight opening 44 is very attractive and serves as a means to draw a crowd so to speak. If desired, the figures of the in-going stream of people may be the same as the outgoing stream of people so that the same people are seen to leave the store as enters the store. However, those people who are seen to enter the store will be laden with bundles when leaving the store, all of which indicates the rapidity with which the people are served while in the store.

As the door 10 may be conveniently opened, the several moving parts of the apparatus may be conveniently exposed and made accessible for the purpose of repair or replacement, or if it is desired to change the figures representing the people this may be conveniently done. Also the cards 22 may be conveniently changed as the same merely fit within slots in the upper portions of the card supporting members 24.

It is to be understood that the form of the invention illustrated and described is to be taken merely as the preferred example of the same and that such minor changes in arrangement and construction of parts may be made as will remain within the spirit of the invention and the scope of what is claimed.

Having thus described the invention what I claim is:—

1. A display device consisting of a shaft, a plurality of cams having hubs mounted on

- said shaft and constituting spacing devices for the cams, said cams being provided with straight and curved edges, the outer ends of said cams between said straight and curved edges being flattened, and article supporting means engaged with said cams and operated thereby, the flattened outer ends of said cams forming a means to hold the article supporting means temporarily in an elevated position.
2. A display device consisting of a shaft, a plurality of cams connected to said shaft and provided with straight and curved edges, the outer ends of said cams between said straight and curved edges being flattened, and article supporting members engaged with said cams and operated thereby, the flattened outer ends of said cams forming a means to hold the article supporting member temporarily in an elevated position, said cams being extended in different directions from said shaft whereby the article supporting members are separately elevated.
3. A display device consisting of a shaft, a plurality of cams having hubs mounted on said shaft and constituting spacing devices for the cams, said cams being provided with straight and curved edges, the outer ends of said cams between said straight and curved edges being flattened, article supporting members engaged with said cams and oper-
- ated thereby, the flattened outer ends of said cams forming a means to hold the article supporting member temporarily in an elevated position, and a casing having a sight opening through which the article carried by said supporting members may be seen.
4. A display device comprising a casing having a sight opening, a shaft carried by said casing, a plurality of cams mounted on said shaft and extending in different directions from the same, vertically movable rods having their lower ends engaged with said cams whereby the rods are separately and independently elevated by said cams, and cards carried by said rods and movable to a position behind said sight opening.
5. A display device comprising a casing having a sight opening, a shaft carried by said casing, a plurality of cams mounted on said shaft and extending in different directions from the same, vertically movable rods having their lower ends engaged with said cams whereby the rods are separately and independently elevated by said cams, cards carried by said rods and movable to a position behind said sight opening, said cams being provided with straight and curved edges, the outer ends of the cams being flattened whereby to temporarily hold the cards in an elevated position.

NED WINKLER.
